UNITED STATES PATENT OFFICE.

MAX B. TERLESKY, OF PORTLAND, OREGON, ASSIGNOR OF ONE-HALF TO JOSEPH REBNER, OF PORTLAND, OREGON.

SHIP-CALKING MACHINE.

1,279,039.

Specification of Letters Patent. Patented Sept. 17, 1918.

Application filed September 14, 1917. Serial No. 191,376.

To all whom it may concern:

Be it known that I, MAX BRUNO TERLESKY, a citizen of the United States, and a resident of Portland, in the county of Multnomah and State of Oregon, have invented new and useful Improvements in Ship-Calking Machines, of which the following is a specification.

My invention is an improvement in ship 10 calking machines, and has for its object to provide a machine of the character specified capable of being moved along the seam between two boards and having means for constraining the same to follow the seam, and 15 having power operated calking chisels for calking the same.

In the drawings:

Figure 1 is a front view of the improved machine, with parts in section;

20 Figs. 2, 3 and 4 are sections on the lines 2—2, 3—3 and 4—4, respectively, of Fig. 1, each view looking in the direction of the arrows adjacent to the line;

Fig. 5 is a section on the line 5—5 of 25 Fig. 2.

In the present embodiment of the invention, a supporting frame 1 is provided having depending legs 2, and within each pair of legs is journaled a shaft 3 having wheels 30 4 for supporting the frame. Between each pair of wheels 4 is arranged a wheel 5 which is adapted to run in the seam 6 between two boards to guide the frame and constrain it to follow the seam. One of the shafts, 35 namely, that at the front of the machine, is provided with a sprocket wheel 6 which is connected by a chain 7 with a wheel 8 on a transmission shaft 9 journaled in the frame. This transmission shaft is driven 40 from a motor 10 mounted on the frame, through friction gearing. The motor shaft 11 has a friction disk 12, which is engaged by disks 13 and 14 on the shaft 9, the disk 13 being feathered on a sleeve 15 on the 45 shaft, while the disk 14 is feathered on the shaft.

Each of the disks 13 and 14 has a tire 16 of material having a high coefficient of friction, as, for instance, rubber, and these 50 tires engage the face of the disk 12 on the motor shaft. The disks 13 and 14 may be moved toward and from the center of the disk 12, by means of levers 17 and 18, respectively, which engage annular grooves 55 in the hubs of the disks. Each of the levers

is pivoted to a toothed sector 19 on the frame, and each lever has latch mechanism co-operating with the sector.

The disk 14 drives the shaft 9, while the disk 13, which is feathered on the sleeve 15, 60 drives a pulley 20 which is secured to the sleeve, and this pulley 20 is connected by a belt 21 with a pulley 22 on one of a pair of feed rollers, the members of the said pair being designated by the reference characters 65 23 and 24. These feed rollers are journaled on the frame, and the calking material, indicated at 25, is fed by the rollers from a supporting reel 26 journaled on the frame. A feed plate 27 extends from the rollers to 70 the seam, the lower edge of the feed plate being in such position that the calking material will pass from the plate into the seam, and the upper end of the plate is at the space between the rollers. The plate is inclined as shown, and is tapering, gradually 75 increasing in width toward its bottom.

The calking chisels 28 and 29 are connected with the piston rods 30 of pistons 31 which are mounted in cylinders 32 supported 80 on the frame. These cylinders are supplied with motive fluid through a pipe 33 which leads from the motor 10, and valves 34 are provided in the pipe for controlling the flow of motive fluid to the chisels. Each 85 chisel is pivoted to the piston rod, as indicated at 35, and a spring 36 is arranged adjacent to the chisel 28, the said spring normally pressing the lower edge of the chisel toward the feed plate, thus insuring the 90 proper feeding of the material. It will be noticed that the shaft of the roller 23 is extended so that the pulley 22 is directly below the shaft 9.

In operation, when the motor is running 95 fluid under pressure may be supplied to the cylinders, reciprocating the pistons and the chisels. The rollers 23 and 24 feed the calking material to the seam, and as the chisels 28 and 29 are reciprocated the material will 100 be wedged into the seam. The speed of the feed may be controlled by the lever 17, while the machine may be moved as a whole longitudinally of the seam through the driving connection 7, this connection being controlled 105 by the lever 18. It will be understood that the chisel 29 may be omitted if desired. The frame is extended above the pipe 33 to form a handle 37 for convenience in manipulating the machine.

I claim:

1. A calking machine comprising a wheel supported frame, a motor on the frame, a driving connection between the motor and the wheels for driving the wheels, power operated chisels supported by the frame and driven by the motor, means for connecting the chisels or the wheels to the motor, means for constraining the chisels to follow the seam to be calked, means on the frame for supporting a strip of calking material, means controlled by the motor for feeding the strip, means for varying the rate of feed, and means for guiding the strip to the seam at the chisels, said means comprising an inclined plate leading from the feeding means to the seam to be calked, the chisel being pivotally mounted and normally spring pressed to engage the plate.
2. A calking machine comprising a wheel supported frame, a motor on the frame, a driving connection between the motor and

the wheels for driving the wheels, power operated chisels supported by the frame and driven by the motor, means for connecting the chisels or the wheels to the motor, means for constraining the chisels to follow the seam to be calked, feed rollers for the calking material offset laterally from the seam, and an inclined feeding plate leading from the rollers to the seam at the chisels.

3. A calking machine comprising a frame, chisels supported by the frame, means for driving the chisels, said chisels being pivoted to the said driving means to swing transversely of the seam to be calked, feeding means lateral to the chisels, a feed plate leading from the feeding means to the seam to be calked, and springs pressing the chisels into contact with the plate.

MAX B. TERLESKY.
